UNITED STATES PATENT OFFICE.

CALVIN ERNEST BOLT, OF RAMSEY, ILLINOIS.

ROAD-DRAG.

1,086,252.

Specification of Letters Patent.

Patented Dec. 2, 1913.

Application filed October 21, 1912. Serial No. 726,998.

To all whom it may concern:

Be it known that I, CALVIN ERNEST BOLT, a citizen of the United States, residing at Ramsey, in the county of Fayette and State 5 of Illinois, have invented certain new and useful Improvements in Road-Drags; and I do declare the following to be a full, clear, and exact description of the invention, such as will enable others skilled in the art to 10 which it appertains to make and use the same.

This invention relates to improvements in road drags of the sled type.

The principal object of the invention is to 15 provide a simple, durable and economical machine of light draft which will effectively gather the earth from the sides of the road and distribute it at and in the direction of the crown or center of the road, thus building 20 the road up in the most approved manner.

Another object of the invention is to provide improved leveling means for a drag of this character under the control of the operator. 25

Another object is to provide improved cutting or scraping blades which will operate in all kinds of weather.

With these and other objects in view, the 30 invention consists of certain novel features of construction, combination and arrangement of parts as will be more fully described and claimed.

In the accompanying drawings:—Figure 35 1 represents a perspective view of a drag constructed in accordance with this invention with the platforms omitted. Fig. 2 is a longitudinal vertical section thereof taken on line 2—2 of Fig. 1 and with the platforms 40 omitted. Fig. 3 is a front elevation thereof.

In the embodiment illustrated two divergent side members 1 and 2 are shown which converge at their rear ends and diverge at their front ends and are connected 45 at both ends of the drag and at an intermediate point by means of cross bars 3, 4 and 5, respectively. The ends of the rear cross bar 3 preferably extend beyond the side members 1 and 2 and are designed to 50 support platforms 6 and 7 shown in Fig. 3 to receive ballast for weighting the drag down when desired. The front ends of the side members or runners 1 and 2 are preferably curved inwardly as shown clearly in 55 Figs. 1 and 3 and are provided on their inner faces with curved cutting blades 8 and 9

of any suitable or desired length. These cutting blades 8 and 9 reinforced by the curved thin edges of the runners will cut into the road bed and serve as scrapers for 60 gathering up the cut material to the center of the road and will operate either when the ground is frozen or on soft ground equally well.

A running board 10 extends longitudinally of the drag preferably about midway the width thereof and is secured to the cross bars 3, 4 and 5, as shown in Fig. 1. To one edge of this running board 10 at its front end are secured a plurality of laterally extending longitudinally spaced pins or 65 studs 11 for a purpose to be described.

A leveling device in the form of an end gate 12 is shown mounted at the rear end of the drag between the side members 1 and 2 70 and hingedly connected at its upper edge to the cross bar 3, said gate being substantially the same width as the side members or runners 1 and 2. A heavy coil spring 13 is secured at one end to the runner board 10 and 75 at its other end to the end gate near its lower edge as shown in Fig. 2, and is designed to exert its tension to hold said gate in lowered position.

A bell crank lever 14 is fulerumed to the 80 rear end of the drag preferably between longitudinally extending lugs 15 at the rear end of the running board 10. One arm of this lever 14 is connected with the end gate 12 preferably by links 16 as shown in Figs. 90 1 and 2. The other arm of this lever 14 is extended and detachably connected by a bar 17 with one of the studs 11 which project from the running board 10 at its front end. This bar 17 is pivotally connected with the 95 arm of the lever 14 and is provided at its free end with an eye 18 for detachable engagement with the studs 11, said studs being preferably bent or curved longitudinally to facilitate the retention of the eye 18 of the 100 bar 17. This lever 14 and bar 17 are designed to control the opening movement of the leveler or end gate 12 and to hold it in adjusted position against the tension of the 105 spring 13 as shown clearly in Fig. 2.

By employing a plurality of longitudinally spaced pins 11, it will be obvious that the gate may be opened to a greater or less extent as may be desired and secured in adjusted position by engaging the eye 18 of 110 the bar 17 with one of said pins.

Suitable clevises 19 are secured to the

front cross bar 5, preferably near its opposite ends and are adapted to be connected with a whiffle or double-tree to which the draft animals are to be attached.

- 5 In the use of this drag, the horses having been hooked to the front end thereof, it is drawn over the road and the knives or cutting blades 8 and 9 cut into the ground at opposite sides of the road and scoop up 10 the dirt which is gathered in by the converging side beams 1 and 2 and disposed in the center of the road where it is engaged by the leveler 12 which smooths and spreads it evenly over the crown of the road and 15 thus the roads may be kept smooth and in good condition at all times of the year and at a minimum cost.

While I have described my invention with more or less minuteness as regards details 20 and as being embodied in certain precise forms, I do not desire to be limited thereto unduly any more than is pointed out in the claims. On the contrary, I contemplate all proper changes in form, construction and 25 arrangement, the omission of immaterial elements and substitution of equivalents as circumstances may suggest or render expedient.

I claim as my invention:—

- 30 1. A road drag having laterally spaced side members, a leveling gate hinged between said members and extending transversely of the drag; a resilient element for holding said gate normally closed and means for opening said gate against the tension of 35 said element and holding it in adjusted position.

2. A road drag comprising laterally spaced side members, cross bars connecting said 40 members, an outwardly opening end gate hinged at its upper edge to the rear cross bar, a coiled spring connected at one end to

the lower end of said end gate and at its other end to a fixed support and a lever fulcrumed on said drag and connected with 45 said end gate for opening said gate against the tension of said spring and means for locking said lever in adjusted position.

3. A road drag comprising laterally spaced side members, cross bars connecting said 50 side members, a running board extending longitudinally of said drag and secured to said cross bars, a leveling gate depending between said side members and hinged connected at one edge to one of said cross 55 bars, a coiled spring connected at one end to the inner face of said end gate and at its other end to the lower face of said running board, and adjustable means connected with said gate for holding it in open position 60 against the tension of said spring.

4. A road drag comprising laterally spaced side members, cross bars connecting said 65 side members, a running board extending longitudinally of said drag and secured to 70 said cross bars, a plurality of longitudinally spaced pins extending laterally from one edge of said running board, a leveling gate depending between said side members and hinged connected at one edge to one of 75 said cross bars, a coiled spring connected at one end to the inner face of said end gate and at its other end to the lower face of said running board, and a lever connected with said gate and with one of said pins for holding the gate in adjusted position.

In testimony whereof I have hereunto set my hand in presence of two subscribing witnesses.

CALVIN ERNEST BOLT.
